UNITED STATES PATENT OFFICE.

PATRICK HENRY DAVIS, OF LEONIA, NEW JERSEY, ASSIGNOR TO CHAMPION DISH WASHING MACHINE COMPANY, OF JERSEY CITY, NEW JERSEY, A CORPORATION OF NEW JERSEY.

DISHWASHING MACHINE.

Application filed April 20, 1923. Serial No. 633,397.

This invention relates to improvements in dish-washing machines, and more particularly to machines of this character wherein the wash water and suds are forced through 5 a manifold and delivered onto the dishes in the form of a spray, the object of the invention being to provide an improved manifold whereby a rinsing spray of clear, clean water or steam may be delivered on the 10 washed dishes, and which manifold is readily removable from the machine.

With the foregoing and other objects in view, which will appear as the description proceeds, the invention consists in the novel 15 features of construction and combination of parts which will be more fully described hereinafter and particularly pointed out in the claims.

In the drawings accompanying and forming 20 part of this specification,

Figure 1 is an end elevation of a dish-washing machine showing the outside pipe connections;

Fig. 2 is a sectional end view showing the 25 upper and lower manifolds in operative position;

Fig. 3 is a sectional view taken approximately on the line 3—3 of Fig. 4;

Fig. 4 is a plan view, on an enlarged 30 scale, of the manifold, showing the same partly broken away and in section, and also showing a portion of the end wall of the machine in section;

Fig. 5 is a plan view of one of the supporting connections for the manifold;

Fig. 6 is an end view of the connections shown in Fig. 5;

Fig. 7 is a plan view of the connecting sleeve for the main head of the manifold;

Fig. 8 is an end view of the sleeve shown in Fig. 7;

Fig. 9 is a sectional view taken on the line 9—9 of Fig. 4 looking in the direction of the arrow; and,

Fig. 10 is a longitudinal sectional view through the manifold head looking in the direction of the outlet pipes thereof.

The same characters of reference designate the same parts in the different figures of the 50 drawings.

As hereinbefore stated, the invention has

to do more particularly with the manifold and its supporting means, and therefore the washing-machine will be described only in a general way.

Referring to the drawings, 2 designates the side walls and 3 the end walls of the machine, the interior of which is provided with a vertical partition 4 so as to form a tank 5 and an inclined partition 6 for draining back to the tank. A drain pipe 7 communicates with the tank at the bottom thereof, the communication being controlled by a valve which is operated by means of a hand lever 8, said pipe also communicating 60 with an overflow 9 which enters the tank near the top thereof.

In the embodiment of the invention shown in the drawings, I have provided what may be termed a "duplex" manifold; that is to say, a manifold in which two separate channels are provided, one for the wash water and suds and the other for rinse water. Referring especially to Fig. 4, the manifold is cast in one piece and comprises a double 75 tubular head 10, 11, from which extend at right-angles thereto perforated branches 12 and 13, respectively. The manifold is so formed that the head portion 11 lies in a plane above the portion 10, as shown in Fig. 3, while the respective communicating pipes 13 and 12 are all in the same horizontal plane, as shown in Fig. 9. The head portions 10 and 11 are divided at their inlet ends to provide two separate and distinct 80 portions 17 and 16 in approximately the same horizontal plane.

For supporting the manifold a connecting sleeve 18 is provided, said sleeve having a threaded portion 19 at one end thereof 90 adapted to pass through an opening in the end wall of the casing and connect with a standpipe 20 at the outside of said casing, and which standpipe communicates at its lower end with the interior of the tank. 95 The sleeve 18 is provided with a boss 21, preferably formed so as to receive a wrench for turning it and adapted to clamp the end wall between it and the end of the standpipe. The smooth portion 18 of the sleeve 100 is adapted to fit snugly within the inlet end 17 of the head 10 and form therewith a

watertight joint, while permitting said portion 17 to rotate on the sleeve when the manifold is to be removed from the machine. A second tubular connecting member is provided for supporting the inlet portion 16 of the head 11, this member having a threaded end 22 adapted to pass through an opening in the end wall 3 and connect with a standpipe 23, this connecting member also having a boss 24 formed to receive a wrench and adapted to clamp the end wall 3 between it and the standpipe. Formed integral with the lower portion of the boss 24 is a seat-forming member or socket 25 which is provided with an internal semi-annular groove adapted to receive the flanged or shouldered end of the head 16 and retain the same in watertight engagement with the boss 24, as shown clearly in Fig. 4. It will be understood, of course, that provision may be made for the reception of suitable packing between the end of the connecting sleeve 18 and its seat in the head portion 17, as well as between the head 16 and the member 24, should such packing be necessary to make the connections watertight.

From the foregoing it will readily be seen that the manifold is maintained in its operative, horizontal position by engagement 30 of the head portion 16 with its supporting socket 25, and that the manifold can readily be removed from the machine by rotating the manifold on its sleeve support 18 sufficiently to carry the head 16 out of its socket, whereupon the manifold may be removed by pulling the same in a direction axially of the head, thus causing the head 17 to slip off from its sleeve 18. The machine is provided in the side wall of the washing chamber with 40 an opening which is closed by a removable door 26 having a handle 27 for operating the same, through which opening access is had to the interior of the washing chamber for removing and replacing the manifold as well as the articles to be washed.

It will be seen by referring to Fig. 2 that a pair of manifolds, such as that described, are provided, one above the other, the upper sides of the lower pipes 12 and 13 and the 50 lower sides of the upper pipes 12 and 13 being perforated so that a spray of washing fluid is directed above as well as below on articles adapted to be supported therebetween. The supporting means for such articles has been omitted from the drawings for the sake of clearness, since it forms no part of the present invention. It will be observed that, owing to the curved form of the top portion of the casing as shown here- 55 in, the upper manifold cannot be swung upwardly. Consequently the socket 25 for receiving the head 16 of this manifold is placed with its open side down, and the manifold is supported by a removable pin 28 60 or other suitable means secured in the end

wall of the casing in position to engage the under side of the pipes 12 near their free ends.

For facilitating the cleaning of the pipes 12 they are open at their free ends, said ends being internally threaded and each provided with a screw plug 29 for closing the end when the manifold is in operation. The head 10 is provided with a threaded opening in alignment with each of the nozzles, which openings are closed by screw plugs 30. It will thus be seen that on removal of the plugs 29 and 30 a cleaning brush or wire may readily be passed through the nozzles for dislodging grease or other matter which may have accumulated therein. The laterally extending curved portions 31 formed on the rinsing pipes 13 in the present instance are merely for convenience in casting, as they serve to support the core. After the casting is completed, these portions are threaded interiorly and each provided with a plug 32.

Referring now to Fig. 1, each of the standpipes 20 and 23 enters the casing of the machine in three places. At their upper ends they connect respectively with the inlet heads 17 and 16 of the upper manifold, while intermediate their ends they are each provided with a T-coupling 33 and 34 respectively, which communicate with the inlet heads of the lower manifold. At their lower ends the standpipes communicate with the tank 5, the standpipe 20 being connected with a suitable pump 20* for forcing the fluid contained in the tank up through the standpipe and the head 17 and into the pipes 12, a valve 35 having an operating handle 36 being provided for controlling the passage of the cleansing fluid through the standpipe 20. The standpipe 23 is provided at 37 with a similar valve and operating handle. This latter standpipe, however, is intended for supplying a stream of rinsing water, and hence does not receive its supply from the tank. The standpipe 23 is provided with a pair of T-couplings 38 and 39 for connection respectively with a water supply and a steam supply (not shown), and between said T-couplings and the point where the lower end of the standpipe enters the tank a valve 40 is provided for controlling the supply of water or steam to said tank.

In order to fill the tank, the valve 37 is closed and valve 40 opened, whereupon the fluid, either water or steam, will pass into the lower portion of the standpipe 23 and thence into the tank 5. When there is sufficient fluid in the tank, the valve 40 is closed and the valve 35 opened. The pump may then be started, whereupon the cleansing fluid will be forced through the standpipe 20, inlet 17, head 10, and pipes 12, and, after being sprayed upon the dishes, will fall onto the inclined partition 6 and be returned to

the tank. After the refuse is all washed from the dishes the pumping of the wash fluid is discontinued. The valve 37 may now be opened, valve 40 remaining closed, whereupon clean, clear water will be admitted through the inlet 38, or steam through the inlet 39, into pipe 23 passing through connection 16, manifold 11 and pipes 13 where it is sprayed through the openings therein onto the dishes, the preferred practice being first to admit water for rinsing the dishes and then steam for facilitating the drying thereof. The rinsing water and condensed steam, after being sprayed on the dishes, will fall onto the partition 6 by which it is directed into the tank 5. This rinsing water and steam will thus replenish the wash water in the tank, the overflow pipe 9 serving to maintain the water at the proper level in the tank.

While I have described in detail the structure herein illustrated, it is to be understood that I do not limit my invention to the precise features of construction shown, as I am aware that many mechanical changes and modifications may be made therein without departing from the spirit and scope of the claims appended hereto.

Having thus described my invention, what I claim is:

1. The combination in a dish-washing machine of a casing means for supplying a cleansing liquid and a rinsing liquid respectively to the dishes to be washed, including a one-piece manifold spaced from the casing and comprising a head having a pair of independent channels extending axially therethrough adapted to be connected to the cleansing and to the rinsing liquid supply respectively, branches integrally attached to the head and extended transversely across the casing above the space for the dishes which branches are also provided with a pair of separated channels respectively communicating with one of the channels of the head, said branches being provided with a plurality of apertures through which the cleansing and rinsing liquids can respectively flow onto the dishes.
2. The combination in a dish-washing machine of a casing means for supplying a cleansing liquid and a rinsing liquid respectively to the dishes to be washed, including a one-piece manifold spaced from the casing and comprising a head having a pair of independent channels one above the other and extending axially therethrough adapted to be connected to the cleansing and to the rinsing liquid supply respectively,

means for horizontally supporting the manifold from one wall of the casing, branches extended transversely across the casing below the space for the dishes which branches are also provided with a pair of separated channels disposed in the same horizontal plane respectively communicating with one of the channels of the head, said branches being provided with a plurality of apertures through which the cleansing and rinsing liquid can respectively flow onto the dishes.

3. In a dish washing machine, the combination of a casing means for supplying a cleansing liquid and a rinsing liquid respectively to the dishes to be washed, including a pair of spaced-apart inlet members communicating with the interior of the casing, a manifold having a head portion with superposed channels therein and spaced apart inlet portions having channels communicating respectively with said superposed channels, connecting means for supporting said manifold and for establishing communication between the said inlet members and inlet portions, said connecting means being adapted to permit removal of said manifold when the latter is partially rotated thereon.

4. In a dish washing machine the combination of a casing means for supplying a cleansing liquid and a rinsing liquid respectively to the dishes to be washed, including a pair of spaced-apart inlet members communicating with the interior of the casing, a manifold having a head portion with two superposed channels therein and a pair of laterally extending channeled inlet portions communicating respectively with the upper and lower channels in said head portion, hollow connecting means between said inlet portions and the inlet members, said means including a sleeve portion forming a pivotal support for the manifold and a socket portion for retaining the manifold in operative position.

5. In a dish washing machine, a casing means for supplying two separate fluids to the interior of the casing, a one-piece manifold having separate inlet members and a plurality of spray forming members, connecting members for establishing communication between the supply means and said inlet members and including a hollow pivotal support for one of said inlet members and a socket support for the other inlet member.

In testimony whereof I have signed my name to this specification.

PATRICK HENRY DAVIS.
